UNITED STATES PATENT OFFICE.

JOHN P. WEIS, OF BROOKLYN, NEW YORK, ASSIGNEE, BY MESNE ASSIGNMENTS, TO
METROPOLITAN SEWING-MACHINE COMPANY, A CORPORATION OF NEW YORK.

FEEDING MECHANISM FOR SEWING-MACHINES.

1,088,752.

Specification of Letters Patent. Patented Mar. 3, 1914.

Application filed April 23, 1903. Serial No. 153,907.

To all whom it may concern:

Be it known that I, JOHN P. WEIS, a citizen of the United States, residing in Brooklyn, county of Kings, and State of New York, have invented a new and useful Improvement in Feeding Mechanism for Sewing-Machines, of which the following is a description.

This invention relates to feeding mechanism for sewing machines, and particularly to that class of feeding mechanisms known as "four-motion feeds." It will be obvious, however, from the following description, that the invention is not restricted to four motion feeds, but may be applied to feeding mechanisms which have the two movements, viz., to and fro, for the purpose of advancing the work.

The object of my invention is to provide a feeding mechanism with means whereby the same may operate upon work either entirely in advance of the path of reciprocation of the needle, or entirely behind the path of reciprocation of the needle, or operate upon the work both before and behind the path of reciprocation of the needle in the manner of an ordinary feeding mechanism.

Another object of my invention is to provide a ready means whereby the feed may be caused to operate upon the work either in front of or behind the path of reciprocation of the needle, during the operation of the machine, without affecting the stitching operation of the latter; and these adjustments, which may be extremes, to be accomplished instantly and from one to the other according to predetermined arrangement of the adjusting means.

With these objects in view, and others which will appear during the course of this description, my invention consists in the parts, features and combinations herein-after described and claimed.

In the drawings: Figure 1 is a plan of a portion of a sewing machine showing my feeding mechanism applied thereto, it being understood that the ordinary elements of the machine are omitted in order to portray my invention without confusion of parts; Fig. 2 is an end elevation of the feeding mechanism, showing the coöperation of the presser-foot thereof, and also showing the throat-plate in section; Fig. 3 is a rear elevation of the parts shown in Fig. 2; Fig. 4

is a side elevation of the feed-bar and its immediate actuating parts, the driving shaft and the shaft for supporting the feed-bar being shown in section; Fig. 5 is an end elevation of the feeding mechanism showing the adjustment of parts for producing a stitching action, viz., with the feed-dog 15 inclined upwardly from front to rear; Fig. 6 is a view similar to Fig. 5 showing the adjustment of the feeding mechanism so as to produce ordinary feed, viz., with the feed-dog arranged to operate in a horizontal plane while feeding the work; and Fig. 7 is a view similar to Figs. 5 and 6 showing the adjustment of the feeding mechanism so as to produce fulling, viz., with the feed-dog inclined downwardly from front to rear.

The character of machine, to which my invention may be applied, not being important, I have merely shown the essential parts of the feeding mechanism in the drawings, it being understood that the feeding mechanism of my invention may be applied and adapted to most of the sewing machines now in use. And it may be further noted that the feeding mechanism of my invention has a particular use in sewing machines wherein it is desired to pucker or full one portion of the work upon another; or wherein it is desired to stretch, or distend one portion of the work upon another; or wherein it is desired to alternately full and stretch one portion of the work upon another.

The driving shaft is indicated by 1, and carries at its forward end a disk 2, having a diametric slot 3, in which is adjustable a block 4, connected in the usual manner with one end of the pitman 5, having its other end journaled upon the shaft 6, which in turn is journaled in the upper end of a rocking frame 7, suitably pivoted or journaled in the bed-plate 8, by means of a shaft 9, fixed thereto by screw 9^a. The shaft 1, also carries near its forward end an eccentric 10, calculated to give the vertical movement to the feed-dog by coöperating with a bracket 11, secured by means of screws, or otherwise, to the under side of the feed-bar 13, said bracket 11, together with a shoe 14, at the bottom of the feed-bar 13, engaging said eccentric and affording the bearing surfaces therefor. At its forward end the feed-bar carries the dog 15, adjustably connected to said bar by the screw 16, in the usual manner. At its rear end, the bar 13, is provided

85

110

with a screw-threaded aperture 17, in which operates an adjustable screw 18, for a purpose hereinafter stated. Between its ends the feed-bar has pivoted thereto a lever 19, by means of a pin 20, passing through said lever and also through a lug 21, carried by said bar. The lever 19, extends rearwardly and is fulcrumed upon the shaft 6, carried by the upper end of the rocking frame 7.

10 Between its ends, the lever 19, is guided and steadied by lugs 22, carried by the feed bar 13, keeping the two in proper relation and providing a firm and compact structure. The lever 19, is extended beyond its fulcrum 15 and said extension 23, is provided with a smooth bored aperture 24, through which freely works the adjustable screw 18, the head 25, of the latter affording a limitation to the movement of the extension 23, on one 20 side, and the jam-nut 26, affording a like limitation on the other side.

Journaled upon the shaft 6, is a manipulating lever 27, the same having a downwardly extending heel 28, against which 25 bears the upper end 29, of a coiled spring 30, surrounding, and held in position by means of, the shaft 9. The tension of the spring 30, is regulated and controlled by means of a collar 31, having on its inner face a diametric lug or feather 32, which may engage any one of several diametric slots in the bearing 33, of the rocking frame 7. The set-screw 34, tapped through the collar 31, and engaging the shaft 9, holds said collar 30 from longitudinal movement on said shaft and also retains the spring in its proper position on the shaft and holds the same from longitudinal movement on the latter. One 35 or more apertures 35, are provided in the collar for the insertion of an implement with which the collar may be rotated to increase or decrease the tension of the spring 30. Thus the spring 30, normally holds the lever 27, raised, or in the position illustrated in 40 Fig. 2, by the engagement of the end 29, of said spring with the heel of said lever. The lever 27, is provided with a slot 36, which cooperates with a pin or screw 37, carried by the feed bar 13, thus enabling the lever 45 27, to raise or lower the feed-bar and change the point of contact of the feed-dog with the work. The lever 27, is operated by means of a chain, or other suitable connection 38, connected to said lever as shown in Fig. 2, 50 and at its lower end connected to either a treadle or knee-rest,—a treadle 38^a being shown,—whereby the same may be readily operated from below the bed-plate. The spring 30, will normally hold the lever in 55 one extreme of adjustment, and the other extreme or any intermediate adjustment is readily and quickly obtained by depressing the lever through the medium of the chain 38, as described.

60 65 A suitable presser-foot 39, cooperates with

the feed, the same being carried by the presser-bar 40, and the needle 41, reciprocates in substantially the path illustrated in Fig. 2.

From the above described mechanism, it 70 will be clear that the feed-dog may be held in a horizontal plane, by a proper adjustment of the parts described, thus making it perform the ordinary functions of a four-motion feed by engaging the work throughout its length, both in front of and behind the needle. By properly setting the adjustable screw 18, and subsequently setting the nut 26, the rear end of the feed-bar may be depressed, thus causing the heel 42, of the 80 dog to descend and the toe 43, thereof to rise relatively to the horizontal plane in which the cloth-plate and work lie,—see line *a*, Fig. 4. This causes the dog to engage the work in advance of the path of reciprocation 85 of the needle and produces uniform pucker- 90 ing, or fulling in the work, which will be caught and maintained by the stitching as the work is advanced; the degree of the pucker- 95 ing, or fullness will obviously depend upon the adjustment of the feed movement. By a reverse adjustment of the screw 18, and a proper adjustment of the nut 26, the rear end of the feed-bar will be caused to rise and the toe of the feed-dog will be 100 caused to descend and its heel to rise relatively to the horizontal plane of the cloth-plate and the work,—see line *b*, Fig. 4. This will cause the heel of the feed dog to engage the work in rear of the path of reciprocation of the needle, thus causing the work to be stretched during the operation 105 of stitching, and the degree of the stretching action obviously depending upon the adjustment of the feed movement.

Having established a given feed-stroke, or length of feed, for the feed-bar, or set the block 4 in disk 2 so as to give a uniform feed-movement of, for example, one-eighth of an inch, or eight stitches to an inch, 110 variations of said stroke, or length of feed, can be obtained, both behind and in front of the needle, by adjusting the screw 18 and setting the nut 26 as above described; that is to say, proportionately with the tilt of the feed-dog, the engagement of the feed-surface of said dog on the work will be lessened, 115 resulting in lessening or reducing the feed-movement, or extent of feed of the work. This will be clear when it is remembered that, when the feed-dog is tilted, as indicated by the dotted lines *a* and *b* in Fig. 4, said feed dog operates at an inclination to the work-plate and the work thereon. Hence, the beginning of the stroke of the 120 feed-dog will be with less than its full length in contact with the work pressed against the presser-foot, according to the adjustment of said screw 18 and nut 26, and as the feed-dog continues its movement, when inclined 125 130

according to line *a*, Fig. 4, down an inclined plane, it gradually leaves the work until only its extreme outer end, or toe, is in engagement with the work at the end of the feed-stroke, resulting in puckering or fulling the work in front of the needle. This is more clearly shown in Fig. 7. When the feed-dog is inclined according to the line *b*, Fig. 4, the beginning of the stroke of the feed-dog will be with its extreme rear end, or heel, in firmer contact with the work than the rest of the feed-surface to substantially its middle, and as the feed-stroke continues, the dog will travel up an inclined plane and its feed-surface, to substantially its middle, will be gradually brought into firmer engagement with the work, resulting in stretching the work behind the needle. This is clearly shown in Fig. 5. In both instances the work will be held or retarded to an extent by the pressure of the foot thereon. The extent to which the fulling or stretching will be produced will depend upon the inclination of the feed-dog together with the length of feed-movement, since the degree of inclination of said feed-dog determines the period of operative engagement of the feed-surface of the feed-dog with the work. Fig. 6 shows the normal coöperative feeding relation between the feed-dog and presser-foot.

On reference to Figs. 5, 6 and 7, the difference in the adjustment of the screw 18 and nut 26 will be seen and clearly understood; that is to say, in Fig. 5 the adjustment is for the purpose of stretching the work by so adjusting the parts relatively that the feed-dog for only substantially half its length from the middle to its rear end will engage the work to feed the same practically all in rear of the stitching position. In Fig. 6 the adjustment of the parts is such as to produce a normal coöperation between the feed-dog and presser-foot and cause the work to be fed in the usual manner of a four-motion feed. In Fig. 7 the adjustment is such as to cause the work to be fulled; that is, fed almost entirely by that half of the feed-dog extending from the middle thereof to its front end so that said portion of the feed-dog will engage the work almost entirely in advance of the stitching position, thus causing the work to be pushed up to the stitching position rather than be fed equally to and from the stitching position by the coöperative action of the feed-dog, as with the adjustment of the dog shown in Fig. 6. It will thus be understood that the stretching action is the result of an inclination of the feed-dog, as shown in Fig. 5, and corresponding substantially to the line *b* in Fig. 4 so that the coöperative action of the feed-dog on the work is substantially in rear of the needle; while the fulling action of the feed-dog is the result of the inclination of

said dog, as shown in Fig. 7, and corresponding substantially to that indicated by the line *a*, in Fig. 4, so that the coöperative action of the feed-dog upon the work will be almost entirely in front of the stitching position.

Having determined the extremes of adjustment desired for the work in hand, the mechanism described will enable the operator to quickly manipulate the feed so as to obtain any desired effect on the work, as has been previously described.

It will thus be seen that I have produced a feeding mechanism capable of operating in the ordinary way to advance the work to receive the stitches; also that I have produced a feeding mechanism which is capable of either stretching, puckering or fulling the work. Also that I have produced a feeding mechanism which may be caused to full and stretch the work alternately as desired, or advance the work evenly to and from the stitch-forming mechanism as in the ordinary machine. Obviously, the amount of stretching, or the amount of puckering or fulling given the work will depend upon the extent of the feed stroke for advancing the work relatively to the needle. And I desire to lay stress upon the adaptability of this feeding mechanism for producing the several kinds of work described and performing the several functions above set forth; and also upon the capability of the mechanism to be instantly operated to perform one or the other functions or effects described without affecting the ordinary running or stitching of the machine.

Having thus described my invention what I claim and desire to secure by Letters Patent is:

1. The combination, in a sewing machine having stitch-forming mechanism including a reciprocating needle; and also having a plate for supporting the work; a feeding device operating both in front of and behind the needle; means for actuating said feeding device to traverse the work over said plate; and means coöoperating with one of said parts whereby said plate and feeding device may be tilted relatively from front to rear in the general direction of the feed of the work, whereby the action of said feeding device upon the work may be varied according to the extent to which it is tilted.

2. The combination, in a sewing machine having stitch-forming mechanism including a reciprocating needle, and also having a plate for supporting the work; a feeding device operating both in front of and behind the needle; means for actuating said feeding device to traverse the work over said plate; and treadle-operated means whereby said plate and feeding device may be tilted relatively from front to rear in the general direction of feed of the work, and the degree

- of relative inclination of said plate and feeding device may be varied.
3. A feeding mechanism comprising a feed-bar, a feeding device carried by said bar, and means whereby said feeding device may be tilted bodily from front to rear in the general direction of its feeding movement, whereby the action of said feeding device upon the work may be varied according to the extent to which it is tilted.
4. A feeding mechanism for sewing machines comprising a feed-dog; means for giving said dog feeding movements; and means for angularly adjusting said dog relatively to the horizontal plane of the work-plate, whereby either the toe or the heel of said dog may be caused to contact with the work earlier than the remainder in the feeding movement thereof.
5. A feeding mechanism for sewing machines comprising a feed-bar carrying a dog; means for giving the same feed movement; means for angularly adjusting the feed-dog relatively to the horizontal plane of the work-plate, whereby one end or the other of said dog is either elevated or depressed; and means whereby predetermined extremes of said adjustment may be instantly obtained during the operation of the mechanism.
6. A feeding mechanism for sewing machines comprising a feed-bar carrying a dog, means for actuating the bar to feed the work; means whereby said dog may be tilted bodily relatively to the horizontal plane of the work-plate from front to rear in the general direction of the feed, and the toe of the dog may be caused to contact with and feed the work first.
7. A feeding mechanism for sewing machines comprising a feed-bar carrying a dog; means for actuating the bar to feed the work; means whereby said dog may be tilted relatively to the horizontal plane of the work-plate from front to rear in the general direction of the feed, including means whereby the heel of the dog may be caused to contact with and feed the work first.
8. A feeding mechanism for sewing machines comprising a feed-bar carrying a dog; means for actuating the bar to feed the work; and a lever pivoted to said bar; and means co-operating therewith at one end for regulating the position of the dog so as to cause either its heel or toe to contact with the work.
9. A feeding mechanism for sewing machines comprising a feed-bar carrying a dog; means for actuating the bar to feed the work; and means for causing either the heel or toe of said dog to contact with the work, said latter means comprising a lever pivoted to the feed-bar and an adjustable connection between said bar and lever.
10. A feeding mechanism for sewing ma-
- chines comprising a feed-bar carrying a dog; means for actuating the bar to feed the work; means whereby adjustments of the feed-dog may be obtained so as to either pucker, full, or ordinarily feed the work; and means for controlling the action of the dog whereby predetermined extremes of adjustment may be obtained to change the functional effect of said dog on the work during the operation of the mechanism.
11. A feeding mechanism for sewing machines comprising a feed-bar carrying a dog; means for actuating the bar to feed the work; means carried by the bar whereby extremes of adjustment of the feed-dog may be determined; and means for controlling the action of the dog whereby predetermined extremes of adjustment may be obtained during the operation of the mechanism.
12. A feeding mechanism for sewing machines comprising a feed-bar carrying a dog; means for actuating the bar for feeding the work including a lever pivoted to the bar; means on the bar for guiding and bracing the lever; and means for adjusting the bar so as to cause either the toe or heel only of the dog to operate upon and feed the work.
13. A feeding mechanism for sewing machines comprising a feed-bar carrying a dog; means for actuating the bar to feed the work including a rocking-frame; a pivotal support for the bar independent of said frame; and means operable during the running of the machine co-operating with the bar for changing the angle, and for maintaining any given angle, of the surface of the feed-dog relatively to its normal plane of operation.
14. A feeding mechanism comprising a feed-bar having a feeding surface; means for supporting the bar; means for actuating the bar to feed the work; a spring-controlled lever normally held in a predetermined position; and operative connections between the lever and bar for varying the angle of the feeding surface of said bar relatively to its normal position, whereby various adjustments of said feeding surface may be quickly produced to vary the angle of the feeding surface relatively to its normal position.
15. A feeding mechanism for sewing machines comprising a feed-bar; means co-operating with the said bar for varying the angle of the feeding end thereof relatively to the horizontal plane of the work-plate, including a lever co-operating with the bar for controlling the angle of said feeding end; and means for controlling the normal position of said lever.
16. A feeding mechanism for sewing machines comprising a feed-bar carrying a dog; means for actuating the same to feed the work; means co-operating with the bar for regulating the length of feed; and means for varying the angle of the dog relatively to the horizontal plane of the work-plate.

- to the horizontal plane of the work-plate, whereby the position of the dog may be controlled so as to cause either its heel or toe to contact with the work first.
- 5 17. A feeding mechanism for sewing machines comprising a feed-bar carrying a dog; an adjusting device coöperating with the bar for controlling the angle of the dog relatively to the horizontal plane of the work-plate; a lever having a loose connection with the bar; a spring coöperating with the lever to control its normal position; and means for adjusting the tension of the spring.
- 10 18. A feeding mechanism for sewing machines comprising a feed-bar; means for actuating the same to feed the work; means for regulating the extent of feed; an adjusting device coöperating with the rear end of the bar; a manipulating lever coöperating with the bar; means coöperating with the lever to control its normal position and hold the same under tension; and means for adjusting the said tension.
- 15 19. A feeding mechanism for sewing machines comprising a feed-bar carrying a dog; means for actuating the same to feed the work; means for adjusting the dog so as to vary the angle of its surface relatively to the horizontal plane of the work-plate; and
- 20 independent means operable during the operation of the machine whereby the angle of the dog may be instantly changed.
- 25 20. A feeding mechanism including in combination, a feed bar having a member carrying a feed dog, a feed rocker, an eccentric for raising and lowering said feed bar, a lever pivoted to said rocker and connecting said feed bar to said rocker, means operable from said lever for moving said member carrying the feed dog in an arc around 30 said eccentric for changing the working position of said feed dog.
21. A feeding mechanism for sewing machines including a feed dog, means for supporting it, whereby it may be shifted from inclined to level position and vice versa, means for shifting its position including a pivoted lever connected with the feed dog, means under the control of the operator for operating said lever, and a spring for returning the feed dog to normal position.
- 35 In testimony whereof I have hereunto signed my name in the presence of two subscribing witnesses.
- 40 JOHN P. WEIS.
- 45 Witnesses:
- CHARLES McC. CHAPMAN,
M. B. HOARE.
